ATTORNEY.

UNITED STATES PATENT OFFICE.

SAMUEL DILLARD WEBB, OF WASHINGTON, DISTRICT OF COLUMBIA,
ASSIGNOR TO WILLIAM W. BRIGG, OF SAME PLACE.

COTTON-GIN.

SPECIFICATION forming part of Letters Patent No. 296,659, dated April 8, 1884,

Application filed October 23, 1883. (No model.)

To all whom it may concern:

Be it known that I, SAMUEL DILLARD WEBB, a citizen of the United States of America, residing at Washington, in the District of Columbia, have invented certain new and useful Improvements in Cotton-Gins, of which the following is a specification, reference being had therein to the accompanying drawings.

My invention relates to an improvement in cotton-gins; and it consists in the peculiar combinations, construction, and arrangement of parts hereinafter described, and then pointed out in the claims.

The object of my invention is to overcome the great difficulty which has always existed in the free and uninterrupted operation of cotton-gins, which is to disengage the lint from the gin-saws as fast as dragged off from the bolts in the "roll-box."

Several patents have been lately granted in which leather and fibrous materials are used for cleansing gin-saws, some of which are very effective; but they require much more intelligent attention than can be usually obtained from the ordinary gin-hand, and hence the tenacity with which gin manufacturers and ginners have held to the old-fashioned bristle brush. I have succeeded in overcoming the difficulties which have hitherto prevented the universal use of bristle brushes by the construction and arrangement shown in the accompanying drawings, in which—

Figure 1 is a side view of a gin constructed according to my improvement, with part of the casing removed. Figs. 2 and 3 represent enlarged detail views of the lags, brushes, and portions of the saws, the former being a plan showing the sides of the brushes and the mode of securing the same, while the latter shows the same features, looking toward the ends of the brushes. Fig. 4 is a detail view of a portion of the combing-boards, showing the relation of the combing-pins with the brushes.

A represents the frame of the gin, and B the saws, which may be of any approved form and driven in the usual manner.

C are disks, preferably of wood, secured on a suitable shaft, and provided with lags D, secured thereto in the usual way. Attached to

each of these lags in any convenient manner are the cylindrical brushes E. These brushes are made in the same way as those used for cleaning bottles, lamp-chimneys, &c.—viz., by placing a sufficient quantity of bristles in the opening formed by doubling a wire and then twisting the two strands, by means of which the bristles are securely fastened between the wires and formed into a cylindrical brush. These brushes, having twisted-wire shanks e, forming threads, may be screwed into holes formed in the lags to receive them; or they may be set loosely into holes and there held by set-screws F; or the ends of the wire shank may be untwisted, and then bent and hammered flat upon or into the lag, as shown in Fig. 2.

Owing to the wear of the bristles coming on the ends thereof, they will wear a long time; but when partially worn they may be turned slightly on their axes, so as to bring a new set of bristles into action, and this may be repeated several times until the brushes are worn all around. As the brush-cylinder revolves, the ends of the bristles come in contact with the sides of the saws, and thus exert their cleaning property to the best advantage, and any of the fibers or motes that may adhere to them will be knocked off by wires G, set in two rows on the combing-board H, as shown in Figs. 1 and 4, arranged in the mote-box I, and the fibers not dropped below will be driven into the mote-box and be gathered there by the force of the blast, which passes into said box and escapes through the openings in the ventilating device or wire-gauze J. I prefer to arrange the combing-wires in two rows, the wires of one row being diagonally in line with the wires of the other row, as shown in Fig. 4, and so arranged that one set of wires strikes the brushes a little before the other set strikes the adjacent brushes. By this arrangement of the bristles and pins, as shown, the bristles of each brush strike the pins and are bent, as shown in Fig. 4, and as soon as the brush has passed the pins the elasticity of the bristles causes them to assume their original position, whereby two rapid motions are given to the bristles at each revolution, which enables

them to throw off any matter (such as motes) that may be clinging to them, and this is independent of the jar caused by the striking of the bristles against the pins, which also helps 5 to throw off the motes. I arrange the pins on two rows, for the reason that as only half the pins are in operation at a time less power is required than if they all were acting at once, and, moreover, the jar caused by one row of 10 pins reacts to some extent on the bristles that are on the other side of the brushes.

To those acquainted with the practical use of the cotton-gin it will be seen at once that my improvement is of great value, as my 15 style of brushes will take off all the gummy matter usually adhering to the saws, and as the bristles necessarily become charged with the same and carry it and the motes or napped cotton with them until the bristles strike the 20 pins, when they are opened, as shown in Fig. 4, and the bristles thoroughly separated, because as the bristles get out of contact with the pins they immediately fly back and straighten out with a rapid "flirting" motion, and the 25 jars or shakes these bristles thus get causes them to throw off all matter adhering to them. If it were not for this jarring or shaking, my bristles would soon become surcharged with the naps, gummy matter, sand, &c., and would 30 soon become a solid mass of concreted material, which, besides rapidly wearing out and dulling the saws, would create such an amount of friction on them as to generate heat, electricity, and even flame, which of course should 35 all be avoided in or around a cotton-gin.

Another advantage that my gin has is the location of the mote-box, which is arranged above the flue through which the mass of the lint passes after it is thrown off the brushes, 40 and that the combing or jarring pins are so arranged that any of the napped cotton which may be shook or knocked off of the bristles by the jar given to them by their coming in contact with the pins will fall or be carried into 45 the box by the current caused by the rapid rotation of the brush-cylinder.

I have shown seven lags or brush-holders on the brush-cylinder; but I do not wish to limit myself to this exact number, as I shall 50 probably generally use less, because, owing to the perfection of the operation of these brushes, half the number usually employed will do better work.

The advantages of this invention may be 55 summed up as follows: One-half of the bristles usually required will be saved; speed of brush-cylinder can be reduced one-half; no gumming of saws by damp or immature cotton; no stoppage to clean gin-saws; no napped 60 cotton; more freedom from motes; more durability of bristles; and, to sum up all, much more and better work can be done at less cost.

It is evident that cylindrical brushes may be made of other materials, such as fibers of

whalebone, prepared rattan, and various 65 grasses, horse and other hair, strips of stiff cloth, felt, &c.; but I prefer the bristles on account of their well-known durability.

What I claim as new is—

1. The combination, in a cotton-gin, of a 70 set of saws with a series of brushes constructed to be turned on their axes to bring different sides to bear on the saws, substantially as described.

2. The combination, in a cotton-gin, of a 75 set of saws with a cylinder provided with a series of adjustable brushes having their acting fibers arranged substantially at right angles to the sides of the saws, substantially as described. 80

3. The combination, in a cotton-gin, of a 85 set of saws with a series of cylindrical brushes having their acting fibers arranged at right angles to the sides of the saws, substantially as described.

4. In a cotton-gin, a series of saws and a series of brushes having their acting fibers arranged substantially parallel with the rotating shaft carrying the brushes, in combination with a series of pins pointing substantially toward said brush-carrying shaft, and arranged to be struck by the fibers of the brushes substantially at right angles to their length, whereby the fibers are first jarred and then caused to flirt rapidly back to their original position, 90 as set forth. 95

5. The combination, in a cotton-gin, and with the saws thereof, of a series of cylindrical brushes having their acting fibers arranged substantially at right angles to the sides of the 100 saws, and a series of combing-wires set in different planes, and also arranged substantially at right angles to the acting fibers of the brushes, as and for the purposes set forth.

6. The combination, in a cotton-gin, and 105 with the saws and brushes thereof, of the mote-box I and the comb G H, arranged in said mote-box, substantially as described.

7. The combination, in a cotton-gin, of a 110 brush-cylinder, a device, substantially as described, for cleaning the brushes, and a mote-box arranged to receive the refuse removed from the brushes by the cleaning device, as set forth.

8. The combination, in a cotton-gin, of a 115 brush-cylinder, the pins, a flue to carry away the lint, and a mote-box arranged above the flue, to receive the refuse knocked off the brushes by the pins, substantially as described. 120

In testimony whereof I affix my signature, in presence of two witnesses, this 8th day of October, 1883.

SAMUEL DILLARD WEBB.
